R. A. BREUL.
MITER SQUARE.
APPLICATION FILED DEC. 16, 1919.

Patented Apr. 12, 1921.

Richard A. Breul, INVENTOR

UNITED STATES PATENT OFFICE.

RICHARD A. BREUL, OF BRIDGEPORT, CONNECTICUT.

MITER-SQUARE.

1,374,816.

Specification of Letters Patent. Patented Apr. 12, 1921.

Application filed December 16, 1919. Serial No. 345,375.

To all whom it may concern:

Be it known that I, RICHARD A. BREUL, a citizen of the United States, residing at Bridgeport, in the county of Fairfield and State of Connecticut, have invented a new and useful Miter-Square, of which the following is a specification.

My invention relates to an improvement applied to a sheet metal miter square now 10 in general use by carpenters and builders and known as a figure 4 square, and the object of this improvement is for the purpose of making more serviceable and reliable such a miter square otherwise made according 15 to a former invention of the applicant, Patent No. 768,324 of August 23, 1904, to Richard A. Breul. As will be noted by referring to the annexed drawings and specification, I do provide for, and obtain a clear, 20 unobstructed view of the scale marks and also a more extended and convenient resting surface of the beam flanges by the application of the present improvement, in a manner for such reason differing from a similar 25 invention of the applicant, filed Sept. 5, 1918, and still under consideration by the examiner and patent authorities.

Figure 1 of the drawings gives a face view of a square according to my present 30 improvement. Fig. 2 shows a sheet metal blank of a form necessary to form a cross beam containing my improved features of this device, and Fig. 3 an enlarged end view 35 of a beam after completion of the bending operations. In Fig. 4 is seen a top view, and in Fig. 5 an enlarged end view of the cover attached to the beam flanges.

As apparent by Fig. 1, I employ the usual angular main plate *a*, composed of the 40 squaring shank *a'* and the miter shank *a''*, both united by a properly situated cross beam *b*, the flanges of the latter being enveloped and the open space between these and the beam sides closed up by the cover *c*, 45 Fig. 4.

The present improvement consists in the special formation of the beam blank *b'* represented in Fig. 2, and the consequent form of that beam end engaging the squaring 50 shank, and also includes a corresponding elongation of the beam cover. Beam blank *b'* is folded at its center and again bent outwardly on the dotted lines *f* and *f'*, to have the flanges *b''* and *b'''*, (see Fig. 3) which 55 in turn are engaged and surrounded by the

covering *c*, bent to the shape shown in Fig. 5 and having the slots *g* and *g'*, Fig. 4, to align with the inner space of the beam and to admit the shank portions of the main plate *a*.

On shank *a'*, Fig. 1, is shown a dotted line *x*, indicating, in combination with line *y*, the shape of the beam end as if formed according to said former invention, and it is clearly apparent by consideration of the same lines, that a considerable extension, (see *v*.) of the upper or flange portion of the beam has been effected, as well as a clear triangular space *w*, thus enabling a perfect view of the graduation marks and figures, 70 obscured and hidden away from sight in beams of said previous invention. The line *x'* in Fig. 2 also represents the end edge of a blank as now manufactured, while *e* and *e'* represent the gain of the flanged portion 75 of my present improvement, while the above stated space, *w*, is effected by means of the removal of material from space marked *d*.

The cover *c* is slipped over and along the flanges *b''* and *b'''* of the beam, and thereafter the completed beam entered into its proper place as indicated by the drawing, its outward end engaging the cut out portion *a'''* on miter shank *a''*, and when properly adjusted the beam sides are secured to 80 the inclosed portions of plate *a* by the electric spot welding process, administered by proper currents through points located on the marks *m* and *n*, Fig. 1.

A square thus completed will have the 90 added usefulness of an extended resting surface of the beam flanges, of good service in short and irregular edge work, and will also permit a perfect and clear view of the graduation marks and figures.

I claim.

As an article of manufacture a miter square consisting of a main plate having a miter shank and a graduated shank, of a beam **U** shaped in cross section and having 100 squaring flanges, said beam connecting said shanks, and a loose sheet metal cover engaging and surrounding said squaring flanges, of the end of the beam engaging the graduating arm having the flanged portions 105 and the cover thereon extended, and the **U** shaped part connecting the flanges being cut away, as and for the purpose described.

RICHARD A. BREUL.
